Primary Examiner—Elizabeth A. Albert*(74) Attorney, Agent, or Firm*—Hunton & Williams LLP(57) **CLAIM**

The ornamental design for a transparent transaction card, as shown and described.

DESCRIPTION

FIG. 1 is a front elevational view of a transparent transaction card showing my new design, with the broken lines showing matter for illustrative purposes only and forming no part of the claimed design;

FIG. 2 is a top plan view of the transparent transaction card, with the bottom plan view being a mirror image thereof;

FIG. 3 is a rear elevational view of the transparent transaction card, with the broken lines showing matter for illustrative purposes only and forming no part of the claimed design; and,

FIG. 4 is a left elevational view of the transparent transaction card, with the right elevational view being a mirror image thereof.
